FREQUENCY MULTIPLIER OF THE CAVITY
RESONATOR TYPEDonald R. Hamilton, Garden City, N. Y., assignor
to The Sperry Corporation, a corporation of
Delaware

Application August 9, 1945, Serial No. 609,781

8 Claims. (Cl. 315—6)

1

The present invention is directed toward the art including electron discharge devices operating in the microwave region, for example, at frequencies of the order of 300 megacycles per second and higher.

The present invention is more particularly directed toward improvements in frequency-multipliers for multiplying such microwave frequencies; for example, for multiplying frequencies of the order of 300 megacycles per second to values of the order of 10,000 megacycles per second or higher.

The present invention is also directed toward cavity resonator electron discharge devices for producing such frequency-multiplication.

In the prior art it has been known to use the principle of velocity modulation for periodically varying the velocities of the electrons of a uniform velocity and density electron stream at a predetermined fundamental frequency. Thereafter the varied-velocity electrons are passed through a drift space in which the faster electrons overtake the slower electrons to produce a bunching or conversion of the uniform electron stream to a variable-current electron stream, also known as a density-modulated stream. This bunched or variable-current stream in the prior art may be passed through a pair of grids associated with a cavity resonator or other tuned circuit tuned to a harmonic of the predetermined fundamental frequency, for extracting energy from the stream at such a harmonic frequency. Devices of this type are shown in Hansen and Varian Patent No. 2,281,935, granted May 5, 1942.

The present invention is directed toward improvements in velocity-modulation frequency-multiplier devices of this type. The prior art devices of the type shown in the Hansen and Varian patent inherently produce low power output due to their relatively low efficiency, especially where high frequency-multiplication ratios are desired. The present invention provides novel features for increasing the efficiency and power output of devices of this type.

According to a principal feature of the present invention, three separate tuned circuits, preferably of the cavity resonator type, are caused to interact with the electron stream of the device. The first resonator is tuned substantially to the fundamental frequency to be multiplied and serves to velocity-modulate or periodically vary the velocities of the electrons of the stream. The second resonator or tuned circuit is interposed along the path of the stream in energy-interacting relationship thereto and is separated

2

from the velocity-modulating position of the first resonator by a drift space producing at least partial bunching or conversion to varying current. This second resonator is normally "floating" (that is, unexcited by any external source and unconnected to any load) and is tuned substantially to a harmonic of the fundamental frequency lower than, but subharmonically related to, the desired output frequency. The third resonator is separated from the effective position of the second resonator by a further drift space and is tuned substantially to a harmonic of the resonant frequency of the second resonator. Of course, this is also a harmonic of the fundamental frequency. Output energy is then derived from this third resonator. By the use of the second resonator, in addition to the velocity-modulating resonator and the energy-extracting resonator which were characteristic of the prior art, substantially increased power output may be derived from the stream at the output frequency. This is especially advantageous where high multiplication ratios, such as from fifteen to thirty, are desired.

Accordingly, it is an object of the present invention to provide improved electron discharge apparatus having a plurality of tuned circuits greater than two in number interacting with an electron stream, the successive tuned circuits being each harmonically related to its preceding tuned circuit.

It is another object of the present invention to provide improved frequency-multiplying apparatus of the cavity-resonator type, using a plurality of cavity resonators greater than two in number, each tuned substantially to a harmonic of the resonant frequency of the preceding resonator.

It is a further object of the present invention to provide improved electron discharge apparatus of the velocity-modulation type utilizing a tuned velocity-modulating means and a tuned energy-extracting means harmonically related thereto, and utilizing an intermediate tuned circuit or cavity resonator coacting with the electron stream between the velocity-modulating and energy-extracting means and tuned to a different frequency from these means, this different frequency being integrally related to both the frequencies of the modulating and extracting means.

The invention in another of its aspects relates to novel features of the apparatus described herein for achieving the above and other objects of the invention and to novel principles

employed in this apparatus, as used according to the above-mentioned objects or in the same or different fields.

A further object of the invention is to provide improved apparatus and methods embodying novel features and principles adapted for use in realizing the above objects and also in other fields.

Other objects and advantages of the present invention will become apparent from the specification, taken in connection with the accompanying drawings, wherein

Fig. 1 is an elevational view, partly in longitudinal cross-section, of a preferred form of the present invention;

Fig. 1A is a detail cross-section of Fig. 1 along line 1A—1A thereof; and

Fig. 2 is a similar elevational view of a modified form of the present invention, using an external tuned circuit in the first stage.

Referring to Fig. 1, a first cavity resonator 11 is formed by an outer conducting cylinder 12, a pair of coaxial inner cylinders 13 and 14, and end pieces 16 and 17. A pair of electron-permeable electrodes or grids 18 and 19, preferably of the form shown in Fig. 1A, are mounted respectively in the adjoining ends of tubes 13 and 14 and provide a narrow velocity-modulating gap therebetween. Capacity-defining members 21 and 22 are connected respectively at the ends of tubular members 13 and 14 and provide an effective lumped capacitance which reduces the physical size of the resonator 11 for the desired fundamental frequency to which resonator 11 is substantially tuned. End wall 17 of resonator 11 also contains a flexible diaphragm 23 which permits relative motion between grid 18 and member 21, on the one hand, and grid 19 and member 22, on the other hand, to permit variation or tuning of the resonant frequency of resonator 11. A flange 24 is rigidly connected to tubular member 13, grid 18 and capacity member 21, and is normally urged toward the end plate 17 by a plurality of compression spring members 26 symmetrically disposed about the axis of the device. The motion of flange 24 toward end plate 17 is opposed by a similar plurality of tuning struts or screws 27 having lock nuts 28. It will be apparent that by turning screws 27 in either direction, a corresponding change in the separation of grids 18 and 19 is produced, thereby correspondingly altering the tuning of resonator 11. Resonator 11 is provided with an input coupling loop 29 and an input terminal 31 of the coaxial type coupled thereto, to permit coupling resonator 11 to a suitable source 73 of fundamental frequency energy which it is desired to multiply. By way of example, source 73 may be a relatively low frequency crystal oscillator in combination with conventional frequency-multipliers for multiplying the oscillator frequency to a value suitable for supply to the frequency-multiplier of the present invention.

A second resonator 32 is provided, formed by an outer cylindrical wall 33, an inner concentric tubular member 34, a rigid end wall 36 interconnecting tubular members 33 and 34 and a further end wall 37 connected to the right end of tubular member 14 by a flexible wall portion or diaphragm 38. The end of tubular member 14 carries an electron-permeable electrode or grid 39, and a similar grid or electrode 41 is carried by the adjoining end of tubular member 34 to form a narrow gap therebetween. A capacity-defining member 42 cooperates with diaphragm 38 to

provide capacity-loading for resonator 32, permitting reduction in its physical size. Resonator 32 may similarly be tuned by adjustment of the separation of the gap between grids 39 and 41.

For this purpose a flange 43 is rigidly connected to the outer wall 12 of resonator 11 and is thus rigidly connected to grid 39. A second flange 44 is rigidly connected to outer wall 33 of resonator 32 and is accordingly rigidly connected to grid 41. Flanges 43 and 44, and hence grids 39 and 41, are urged together by a series of tension springs 46 disposed symmetrically around the axis of the device, in a fashion similar to the tuning device of resonator 11. Motion of the grids 39 and 41 toward one another is opposed by a similar series of tuning screws 47 having lock-nuts 48, and the tuning of resonator 32 may therefore be adjusted to a desired value by adjustment of the screws 47. Resonator 32 may be provided with a coupling loop 49 and a coaxial line terminal 51 from which low power of the harmonic frequency to which resonator 32 is tuned may be extracted, such as for the purpose of properly adjusting its resonant frequency, as by use of a wavemeter coupled thereto. Normally, however, terminal 51 and loop 49 are not used and may be omitted, resonator 32 thereby being "floating."

A third resonator 52 is provided in the path of the electron stream and spaced from the second resonator 32. Resonator 52 has a cylindrical outer wall 53 and a concentric tubular inner wall 54. A rigid end wall of resonator 52 is provided by member 36, and the other end wall 35 is formed as a flexible wall portion or diaphragm 56 connected between cylindrical outer wall 53 and the tubular inner wall 54. Member 36 carries an electron-permeable electrode 57 concentrically thereof, which is adjacent to a similar electrode 58 mounted on the adjoining end of tubular member 54. The tuning of resonator 52 is effected in a manner similar to that of the resonators 11 and 32 by biasing spring means 62 and tuning screws 59 having lock-nuts 61. The electron beam, after passing through the gap between grids 57 and 58, is suitably collected on the wall of an electron collector 63, secondary electrons being prevented from disturbing the operation of resonator 52 by a secondary-electron-suppressing grid 64.

A cathode 66 cooperates with an accelerating or smoother grid 67 mounted in member 13 to form an electron gun upon the application of a high positive potential upon grid 67 relative to cathode 66. The source of this positive potential is schematically indicated by the battery 68 connected between a base prong 69 and ground at 71, cathode 66 being connected to the prong 69. The main body of the device is grounded as at 72, thereby providing a ground connection for the accelerating grid 67. The electron stream thus produced travels successively through the first resonator gap between grids 18 and 19, through the first drift space within tubular member 14, through the second resonator gap between grids 39 and 41, through the second drift space provided by tubular member 34, through the third resonator gap provided by grids 57 and 58, and is then collected by the collector 63.

In operation, resonator 11 is excited at the fundamental frequency f to be multiplied by means of any suitable source connected to its terminal 31, such as the source schematically indicated at 73. This produces a standing electro-magnetic field within resonator 11, which

is tuned substantially to this fundamental frequency. This field produces an alternating electric field and voltage of the fundamental frequency between grids 18 and 19, extending axially of the stream. When the electrons of the stream pass through this field, they are alternately accelerated and decelerated; that is, they are velocity-modulated.

The subsequent passage of these velocity-modulated electrons through the first drift space provided by member 14 permits the faster electrons to begin to overtake the slower electrons, and thereby produces a slight partial bunching or conversion of the velocity-modulated electrons into a varied electron current. As discussed in the above-mentioned Hansen and Varian Patent No. 2,281,935, such a varying electron current contains current components of the fundamental frequency and also of frequencies harmonically related thereto; that is, integral multiples of the fundamental frequency. When such a stream passes across the second gap between grids 39 and 41, a standing electromagnetic field of the harmonic frequency $n \times f$ (where n is an integer and f is the fundamental frequency) to which resonator 32 is substantially tuned is produced within resonator 32. This field, being produced by the electron stream, automatically builds itself up in such a phase relation relative to the alternating current component of the electron current of frequency $n \times f$ so as to be in phase opposition thereto; that is, the alternating voltage appearing between grids 39 and 41 is in such a sense and has such a phase that when the partially formed electron bunches pass across the second gap, they experience a maximum retarding effect. This action, when followed by passage through the second drift space defined by member 34, results in the electrons of the bunches being concentrated more highly, which in turn produces a higher energy content in the varying-current electron stream at frequencies which are harmonics both of the fundamental frequency and of the harmonic frequency of resonator 32. Accordingly, by the time this varying current electron stream passes through the third gap between grids 57 and 58, the enhanced bunching has taken place so that a greater amount of power can be extracted from the electron stream by the third resonator 52 tuned substantially to a harmonic p of the resonant frequency of the second resonator 32. This output power of frequency $p \times n \times f$ may be extracted from the resonator 52 by means of a coupling loop 74 and is supplied through an output terminal 76 to any suitable load or utilization device 77.

Another embodiment of the invention operating in accordance with the same principles discussed above is shown in Fig. 2, where the same reference numerals, but primed, are used to indicate corresponding structures. In the embodiment of Fig. 2, the first resonator 11 is replaced by an external tuned circuit 11'. For this purpose grid 19' is fixed to the grounded metal envelope of the tube. The adjacent grid 18' is completely insulated from the metallic envelope. Connected between grids 19' and 18' is an input tuned circuit 11', to which is coupled the source 73 of fundamental frequency f . It is to be understood that any suitable type of tuned circuit, such as formed by lumped inductance and capacitance or by a transmission line, may be used as tuned circuit 11'.

Resonators 32' and 52' correspond exactly to resonators 32 and 52 of Fig. 1. Thus, resonator

32' has a pair of grids 39' and 41' separated from grids 18' and 19' by a first drift space formed tubular member 14'. Resonator 52' has a pair of grids 57' and 58' separated from grids 39' and 41' by a second drift space defined by tubular member 34'. Resonators 32' and 52' may be tuned in a manner similar to that described with respect to Fig. 1.

In operation, tuned circuit 11' is again substantially tuned to the input fundamental frequency f . Resonator 32' is tuned substantially to the harmonic frequency $n \times f$. Resonator 52' is tuned substantially to a harmonic of the frequency of resonator 32', that is, to a frequency $p \times n \times f$. The operation of the device of Fig. 2 is the same as that of Fig. 1, and greater amounts of output energy of the frequency $p \times n \times f$ may be derived, as discussed relative to Fig. 1.

While the embodiments of the invention illustrated in Figs. 1 and 2 use three tuned circuits or cavity resonators, it will be understood that the present invention contemplates the use of more than three such circuits, where desirable, the essential relationship being that each such circuit shall have a resonant frequency which is substantially an integral multiple of the resonant frequency of the resonator next adjacent to it toward the cathode.

Since many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

What is claimed is:

1. Ultra high frequency apparatus comprising means for producing an electron stream, a first cavity resonator along the path of said stream and in velocity-modulating relationship thereto, a second cavity resonator along the path of said stream in energy-exchanging relationship thereto and spaced from said first resonator, means defining a field-free space surrounding the path of said stream between said first and second resonators, a third cavity resonator along the path of said stream in energy-extracting relationship thereto and spaced from said second resonator, and means defining a field-free drift space surrounding the path of said stream between said second and third resonators, said first and second space-defining means having a length sufficient to cause the velocity-modulated electron stream to attain substantially maximum bunching at said third cavity resonator, said second resonator being tuned substantially to a harmonic of the resonant frequency of said first resonator and said third resonator being tuned substantially to a harmonic of the resonant frequency of said second resonator.

2. High frequency apparatus comprising means for producing an electron stream, three cavity resonators positioned successively along the path of said stream, the first of said resonators having a frequency characteristic including a fundamental frequency and further being tuned to said fundamental frequency, the second of said resonators being maintained in a floating condition and having a frequency characteristic including a frequency harmonically related to said fundamental frequency and further being tuned to said harmonic frequency, the third of said resonators having a frequency characteristic including a frequency harmonically related to said

harmonic frequency and further being tuned to said frequency harmonically related to said harmonic frequency, and means for extracting energy from said third resonator.

3. Ultra high frequency apparatus comprising means for producing a stream of electrons, three cavity resonators positioned successively along the path of said stream in energy-exchanging relationship thereto, means coupled to the first of said resonators for supplying fundamental frequency energy thereto, said second resonator being floating and tuned substantially to a harmonic of said fundamental frequency, and said third resonator being tuned substantially to a harmonic of said fundamental frequency which is also substantially a harmonic of said first-named harmonic frequency.

4. High frequency apparatus comprising means for producing an electron stream, three pairs of electron-permeable electrodes positioned successively along the path of said stream, the electrodes of each of said pairs being closely juxtaposed to one another to provide narrow gaps therebetween, a cavity resonator coupled to the second of said electrode pairs, a second cavity resonator coupled to the third of said electrode pairs, means coupling a source of fundamental frequency to said first electrode pair, said first resonator being floating and tuned substantially to a harmonic of said fundamental frequency, and said second resonator being tuned substantially to a harmonic of said harmonic frequency, and a load coupled to said second resonator.

5. High frequency apparatus comprising means for producing an electron stream, means along the path of said stream for velocity modulating the electrons thereof at a fundamental frequency, means along the path of said stream spaced from said velocity-modulating means for extracting energy from said stream at a harmonic of said fundamental frequency, and a floating cavity resonator positioned along the path of said stream between said velocity-modulating means and said energy-extracting means and tuned substantially to a frequency which is a harmonic of said fundamental frequency and a subharmonic of said first-mentioned harmonic frequency.

6. Ultra-high-frequency apparatus comprising means for producing a stream of electrons, three

cavity resonators positioned successively along the path of said stream in energy-exchanging relationship thereto, means coupled to the first of said resonators for supplying fundamental frequency energy thereto, said second resonator being floating and having a resonant frequency substantially equal to a harmonic of said fundamental frequency, said third resonator having a resonant frequency substantially equal to a harmonic of said frequency of said second resonator.

7. High frequency apparatus comprising means for producing an electron stream, a first velocity-modulating cavity resonator positioned along the path of said electron stream, said resonator having a frequency characteristic including a fundamental frequency, a second velocity-modulating cavity resonator along the path of said stream, said second cavity resonator being maintained in a floating condition and excited only by said stream and having a frequency characteristic including a first frequency harmonically related to said fundamental frequency, a field-free drift space located intermediate said first and second resonators, a third energy-extracting cavity resonator along the path of said stream, said third resonator having a frequency characteristic including a second frequency harmonically related to said first harmonic frequency, and a field-free drift space located between said second and third cavity resonators.

8. Apparatus as in claim 7, wherein said first cavity resonator is further tuned to said fundamental frequency, said second cavity resonator is further tuned to said first harmonically-related frequency and said third cavity resonator is further tuned to said second harmonically-related frequency.
